UNITED STATES PATENT OFFICE.

MAURICE ARTHUR HARDYMAN, OF CHARLTON, LONDON, ENGLAND, ASSIGNOR TO
JOHN HARLING BAILEY, OF LONDON, ENGLAND.

SOUND BOX FOR TALKING MACHINES.

Application filed April 11, 1922. Serial No. 551,653.

To all whom it may concern:

Be it known that I, MAURICE ARTHUR HARDYMAN, a subject of the King of England, residing at Charlton, London, England, have invented certain new and useful Improvements in Sound Boxes for Talking Machines, of which the following is a specification.

This invention is for improvements in or relating to sound-boxes for talking-machines, and has for its object to provide a sound-box which shall give a fuller and more mellow tone than those commonly employed.

As is well known, a sound-box usually comprises a diaphragm mounted between a front and a back plate, which plates grip it round its edge but are spaced away from it and have central perforations, the perforation in the back-plate being in line with and of approximately the same diameter as the through-way of a tone-arm socket carried by or formed on the back-plate.

According to this invention, such a sound-box is provided with a sound-chamber between the back-plate and the tone arm socket, said chamber being of a diameter approximately equal to that of the operative portion of the diaphragm and, preferably, in depth considerably deeper than the space between the back-plate and the diaphragm.

The presence of this chamber is found to result in a fuller tone which may be still further mellowed by constructing the chamber of non-resonant material, such, for example, as wood.

The front plate of the sound-box having a sound-chamber as described above, may have a small central perforation of diameter only such as is sufficient for the entrance and operation therein of the stylus-lever, instead of the usual large opening, for the purpose of screening the diaphragm from external noises, such as arise from the scratching of the stylus upon the gramophone record.

In the accompanying drawings:

Figure 1 is a central vertical section through the sound-box at right-angles to the plane of the diaphragm;

Figure 2 is a plan of a diaphragm having a circular corrugation, and

Figure 3 is a section through the diaphragm shown in Figure 2 on the line 3—3 of that Figure.

A diaphragm A is mounted between a back-plate B and cover-plate C. The cover

plate C is cup-shaped and accommodates within it the diaphragm A and two spacing rings D. The back-plate B provides a foundation upon which the diaphragm, sandwiched at its periphery between the spacing rings D, is clamped by the plate C.

Mounted on the back of the plate B concentrically with the diaphragm is a circular chambered member E of wood disposed with its open end towards the plate B. The other end of this chambered member is formed with a short tubular extension E¹ in which is a tone-arm socket F. The socket F has a circumferential flange F¹ on its inner end which engages the inner face of the outer end of the chambered member E and through which it is screwed to said outer end. The internal diameter of the chambered member E is approximately equal to the diameter of the operative portion of the diaphragm A, and the interior depth from the back plate B is approximately three times the depth of the space between the diaphragm and the back-plate. The back plate B has in it the usual central perforation B¹ of diameter nearly equal to that of the through-way of the tone-arm socket F.

The plate C has a small central perforation C² through which a stylus lever G operates; otherwise the plate C is imperforate. The stylus lever is mounted in the usual way on the exterior of the sound-box and is attached to the centre of the diaphragm.

In a preferred form of sound-box the diaphragm A is made of some mouldable material such as sheet ebonite instead of the usual mica disc, and is formed with one or more circular corrugations A¹ as shown in Figures 2 and 3.

The ebonite may be of the class usually employed for electrical purposes and is preferably about 1/64th of an inch thick.

The corrugation A¹ is centrally disposed and lies near the periphery of the diaphragm but clear of the spacing rings D when the diaphragm is in place in the sound-box, so that it may flex freely with the operative portion of the diaphragm.

The corrugation may be formed by pressing the ebonite disc into a mould while hot.

By the employment of such a diaphragm, the tone is much improved compared with that when the usual mica disc is used.

I claim:

1. In a talking-machine sound-box, the

combination of a diaphragm, a back-plate behind the diaphragm having in it an opening for passage of sound emanating from the diaphragm, a tubular tone-arm socket 5 whose sound inlet is disposed opposite the opening in the back-plate, and a hollow cavity member of wood interposed between the back-plate and the tone-arm socket so as to provide a sound cavity behind the back-plate and between it and the tone-arm socket inlet, the interior of which cavity member is so dimensioned that the cavity is greater in diameter than the opening in the back-plate and the inlet of the tone-arm socket and greater in depth than the space 10 between the diaphragm and the back-plate, substantially as described.

15 2. In a talking-machine sound-box the combination of a diaphragm, a back-plate

behind the diaphragm having in it an opening 20 for passage of sound emanating from the diaphragm, a tubular tone-arm socket whose sound inlet is disposed opposite the opening in the back-plate, and a hollow cavity-member of wood interposed between 25 the back-plate and the tone-arm socket so as to provide a sound cavity behind the back-plate and between it and the tone-arm socket-inlet, the interior of which cavity member is so dimensioned that the cavity 30 is substantially equal in diameter to the operative portion of the diaphragm and substantially equal in depth to three times the depth of the space between the dia-35 phragm and the back-plate, substantially as described.

In testimony whereof I affix my signature.
MAURICE ARTHUR HARDYMAN.
